WALTER MACRISTY, NEW BRITAIN, CONNECTICUT, ASSIGNOR TO KEENEY MANUFACTURING COMPANY, OF NEWINGTON, CONNECTICUT, A CORPORATION OF CONNECTICUT.

FLOOR OR CEILING PLATE.

Application filed March 19, 1926. Serial No. 95,919.

This invention relates to a floor or ceiling plate, and among the objects of the invention is the provision of an improved article of this nature which is exceedingly simple and rugged in construction and effective and convenient in action, and which is also attractive in appearance and capable of being very cheaply manufactured.

In the drawing accompanying and forming part of the present application I have represented in detail, for purposes of illustration a simple and advantageous form of embodiment of the invention which will be set forth in detail in the following description.

15 Referring to the drawing:

Figure 1 is a perspective view of a form of the device showing it attached to a pipe and resting on the floor.

Figure 2 is a side elevation showing one 20 of the sections as opened.

Figure 3 is a bottom plan view, the dotted lines showing the action of the springs.

Figure 4 is a view from below showing one 25 of the sections as partly opened.

25 The illustrative plate shown herein comprises two complementary semi-circular sections, indicated at 2, each having a usual semi-circular pipe opening therein, these sections being of improved construction and 30 operatively connected in an improved manner, all as hereinafter described.

More particularly considering these sections, it will be noted that one of the same 35 is provided with a usual peripheral flange 3, while the other has a similar flange 4, and that disposed between the ends of these flanges and on opposite sides of the pipe apertures are usual parallel vertical abutting flanges 5 and 6, the flanges 5 being on one

40 member 2 and the flanges 6 on the other. However, it will be noted that the outer ends of each of the flanges 5 and 6, i. e. the ends adjacent the periphery of the section on each side of the pipe aperture, are formed or cut

45 in such manner as to form wings 7 and 8 thereon which each initially extend longitudinally of the flanges, as shown at 7 at the left in Fig. 2. It will also be observed that apertures, herein in the form of perforations

50 11, are provided in the left hand flanges, as shown in dotted lines in Fig. 3 at a point nearer the pipe aperture than the wings on that side of the pipe aperture. Herein, these perforations are also so disposed as to regis-

ter, as are the wings 7 and 8, when two sections are brought together as shown in Fig. 3.

While they do not per se form a part of the present invention and are necessary only in certain uses of the plate, as for example 60 when covering an aperture in a ceiling, it will also be noted that pipe engaging means are provided on each of these sections 2 in the form of semi-circular flanges 9 carrying co-operating pipe engaging springs 10. As 65 shown, the flanges 9 have usual raised portions thereon provided with slots adapted to receive flat pipe springs 10, these springs 10 extending as cords across the semi-circular apertures and having their free ends bent 70 over on the back of the flanges 9, all as illustrated in Figs. 2, 3 and 4. It should, however, be noted that the pipe aperture is made slightly larger than the pipe with which it is intended to cooperate, in such manner as to 75 provide play therebetween, while when a pipe engaging means is provided this is also adapted to permit play between the pipe and the plate sections.

In order operatively to connect two sections 2 to form a plate, the same are pivotally connected in the complementary relationship shown in Fig. 3. Herein, a pivot pin is passed through the set of registering apertures 11 and fastened in position, preferably in such manner as to hold the two sections snugly together with their flanges 5 and 6 in abutment while yet permitting free movement of either section about the axis of the pin. In a preferred form, I utilize a rivet as the connecting means, finding that a rivet, producing as it does heads on each side, is admirably adapted to connect the parts ruggedly in the desired manner, at the same time that it may be cheaply provided and cheaply and quickly connected. As a result of this connection, it will be observed that the parts may be separated by a movement of one or both relative to the pivot rivet 12, and that they are guided in their movement by the flanges 5 and 6, a sturdy construction thus being provided which is adapted to stand up well in service.

In order to hold the parts 2 in their assembled relationship shown in Figs. 1 and 3, 105 I also provide suitable means adapted for connection or disconnection by a movement about the pivot pin 12. Herein, these means

are provided by certain of the wings 7 and 8 previously described, one set of these wings 7 and 8, i. e. that located on the opposite side of the pipe aperture from the rivet 12 and 5 the parallel or unbent wings on that side of the pipe aperture, being bent back laterally, as shown at the right in Fig. 3, so that either wing thereof may be moved into and out of frictional gripping relationship with the 10 other when one or both of the parts 2 move about the pivot 12. Thus, it will be noted that by a single opening or closing movement in one direction the sections may be fully separated or closed without the necessity for 15 confusing movements in different directions.

In the use of my improved construction, when it is desired to attach the plate to a pipe, the sections 2 and 3 are separated by movement relative to the pivot 12 to such an 20 extent as to permit the pipe to engage the spring 10 in the pipe aperture in one half, and the two halves are then brought together by a reverse movement relative to the pivot and automatically held in position by the engagement of the wings 7 and 8 as the parts 25 come together, the springs 10 then gripping the pipe. Similarly, if it is desired to remove the plate, the play around the pipe permits the sections to be separated by movement relative to the pivot 12, which automatically results in the disconnection of the wings 7 and 8 and subsequent full opening 30 of the parts as they are moved relative to the pipe. In either of these operations it will of course be evident that the plate may be moved bodily relative to the pipe into such 35 angular relation to the pipe as to permit the plate section or sections to clear the latter during the closing or opening operation, and that one or both sections may be moved 40 as desired to facilitate their connection on or removal from the pipe.

As a result of my improvement, it will be observed that it is made possible to make the 45 halves very simple and connect them by very simple yet effective connecting means capable of being provided at very small expense. More particularly, it will be noted that the cuts for the wings and the holes for the rivet can be provided in the blank and that 50 no extra parts other than the rivet are required, while the only assembly labor required is the insertion of the rivet adjacent one set of wings and the bending over of the other 55 set of wings. It will also be evident that the connecting means are very rugged and adapted to withstand long use in service. These 60 and other advantages of my improved construction will, however, be clearly apparent to those skilled in the art.

While I have in this application specifically described one form which my invention may assume in practice, it will be understood that the invention may be modified and embodied in various other forms without de-

parting from its spirit or the scope of the appended claims.

What I claim is:

1. A floor or ceiling plate comprising two semi-circular sections having detachable interlocking devices on the front ends thereof and a pivotal connection on the rear ends thereof, said devices and pivotal connection being so constructed and arranged as to prescribe relative movements of said sections 75 in substantially parallel paths in planes perpendicular to the plate and the pivot axis.

2. A floor or ceiling plate comprising two complementary sections, means including a transverse pivot member retaining their adjacent surfaces in substantial parallelism while permitting movement in planes perpendicular to the plate and the pivot axis, and holding means connectable or disconnectable upon movement of a section about 80 said pivot.

3. A floor or ceiling plate comprising two complementary sections, means including a transverse pivot member operatively connecting one set of ends thereof while permitting movement in planes perpendicular to the plate and the pivot axis, and holding means at the opposite ends thereof connectable and disconnectable upon movement of a section about 85 said pivot.

4. A floor or ceiling plate comprising two complementary sections, parallel surfaces on different sections, a transverse pivot member extending through said surfaces and holding the same together while permitting movement in planes perpendicular to the plate and the pivot axis, and holding means connectable or disconnectable by movement about 90 said pivot.

5. A floor or ceiling plate comprising two 105 semi-circular sections, the rear end portions of which are furnished with flanges and a rivet extending through the flanges and preventing lateral opening of the sections while permitting opening movement in planes perpendicular to the plate and about the rivet axis.

6. A floor or ceiling plate comprising two complementary sections, the rear end portions of which are furnished with vertical 110 flanges, and a pivot extending transversely through and connecting said flanges while preventing lateral opening of said sections, said sections being adjustable about said pivot axis into full open or closed positions.

7. A floor or ceiling plate comprising two complementary sections, the rear end portions of which are furnished with abutting vertical flanges and riveted transversely to form a pivot while preventing lateral opening 115 of said sections, and the front end portions of which are provided with interengaging portions connectable or disconnectable by movement about said pivot.

8. A floor or ceiling plate comprising two 120

- sections each having a pipe opening and a vertical flange on the abutting edge thereof on one side of said pipe opening, said flanges each having a perforation therein 5 adapted to register with a perforation in the other, and a pivot pin in said set of perforations preventing lateral opening of said sections while permitting opening movement about the pivot axis.
- 10 9. A floor or ceiling plate comprising two sections each having a pipe opening and vertical flanges on the abutting edges thereof on opposite sides of said opening, certain of said flanges each having a cut end adjacent 15 the periphery of the section bent laterally to form cooperating holding means operative upon section movement perpendicularly of the plate, and a pivot pin connecting the other set of flanges preventing lateral opening 20 of said sections while permitting opening movement about the pivot axis.
10. A floor or ceiling plate comprising a plurality of complementary sections each comprising a member provided with a pipe 25 aperture therein and vertical flanges on its apertured edge on opposite sides of said aperture, said vertical flanges having cut ends at the periphery of the section and one set of ends being bent laterally and overlapping 30 upon movement perpendicularly of the plate while the other set is unbent and provided with a perforation at a point nearer the pipe aperture, and a rivet extending through the perforation in the unbent set of 35 flanges connecting the sections and preventing lateral opening thereof while permitting pivotal movement thereof about the pivot axis.
11. A section for a floor or ceiling plate 40 comprising a member provided with a pipe aperture therein and a vertical flange on its apertured edge on one side of said aperture, said vertical flange including a wing adjacent the periphery of the section and said flange also having an aperture at a point 45 nearer the pipe aperture.
12. A section for a floor or ceiling plate 50 comprising a member provided with a pipe aperture therein and a vertical flange on its apertured edge on one side of said aperture, said vertical flange including a wing adjacent the periphery of the section and said flange also having a perforation at a point 55 nearer the pipe aperture.
13. A floor or ceiling plate comprising a plurality of abutting sections each provided with a pipe aperture therein and vertical flanges on its apertured edge on opposite sides of said aperture, said vertical flanges each having a wing adjacent the periphery of the section and certain of the same having an aperture at a point nearer the pipe aperture than the wing, said wings and aperture of one section registering with the wings and aperture of its fellow and one 60 of said sets of flanges having its wings bent to overlap while the other set of flanges carries connecting means including a connecting portion extending through the inner registering apertures therein. 65
14. A floor or ceiling plate comprising a plurality of abutting sections each provided with a pipe aperture therein and vertical flanges on its apertured edge on opposite sides of said aperture, said vertical flanges each having a wing adjacent the periphery of the section and certain of the same having an aperture at a point nearer the pipe aperture than the wing, said wings and aperture of one section registering with the wings and aperture of its fellow and one 70 of said sets of flanges having its wings bent to overlap while the other set of flanges carries connecting means including a connecting portion extending through the inner registering apertures therein and snugly 75 clamping together said flanges while permitting movement about the rivet to connect or disconnect said overlapping wings. 80
15. A floor or ceiling plate comprising a plurality of complementary sections each having vertical flanges on opposite sides of its pipe aperture with said sets of flanges on different sections abutting, each of said sets of flanges having undercut wings at the periphery of the plate and certain of the same having an aperture nearer the pipe aperture than the wing, and one of said sets of flanges having its wings bent laterally and lying in overlapping relation at an angle to the flange body while the other set 90 of flanges carries connecting means connecting said sections and permitting separation thereof after an initial movement in a plane perpendicular to the plate to separate 95 said overlapping wings. 100
- 105 In testimony whereof I affix my signature.
- WALTER MACRISTY.
